[57] CLAIM

The ornamental design for a growth measuring and display device, as shown and described.

DESCRIPTION

FIG. 1 is a side perspective view of the first embodiment of the growth measuring and display device cutaway to show clearly the transparent front panel and back solid panel;

FIG. 2 is a side elevation of the growth measuring and display device of FIG. 1, the opposite side being identical;

FIG. 3 is a back view of the growth measuring and display device of FIG. 1;

FIG. 4 is a front view of the growth measuring and display device of FIG. 1;

FIG. 5 is a top plan view of the growth measuring and display device of FIG. 1;

FIG. 6 is a bottom view of the growth measuring and display device of FIG. 1;

FIG. 7 is a side perspective view of the second embodiment of the growth measuring and display device cutaway to show clearly the transparent front panel and solid panel;

FIG. 8 is a side elevation of the growth measuring and display device of FIG. 7, the opposite side being identical;

FIG. 9 is a back view of the growth measuring and display device of FIG. 7;

FIG. 10 is a front view of the growth measuring and display device of FIG. 7;

FIG. 11 is a top plan view of the growth measuring and display device of FIG. 7;

FIG. 12 is a bottom view of the growth measuring and display device of FIG. 7.
